W. F. EMERSON
CYLINDRICAL HONING TOOL

1,791,491

Filed April 3, 1929

UNITED STATES PATENT OFFICE

WILLIAM F. EMERSON, OF WILLIAMSVILLE, NEW YORK

CYLINDRICAL HONING TOOL

Application filed April 3, 1929. Serial No. 352,157.

This invention relates to the art of grinding or resizing of the cylinder walls or bores of automobile and like internal combustion motors and consists of an improved honing 5 or grinding tool particularly adapted for performing the operation of grinding with an improved degree of accuracy and in any manner to obtain important advantages over the honing structures as heretofore employed for 10 the purpose.

The important features of the improved device of the present invention include the provision of means for adjusting the effective operating diameter of the honing elements 15 or stones to establish the operating diameter of the tool with reference to varied sizes of cylinder bores to be operated upon; structural provision whereby upon a simple interchange of parts the tool may be adapted successfully to operate upon substantially enlarged cylinder bores thereby to allow of greater utility; and improved arrangement 20 for supporting and adjusting the stones whereby in the honing or grinding operation the stones will be positively adjusted to a given operating diameter and including the provision of a supplemental spring adjustment arranged to impart expanding movement to the stones under a relatively 25 light pressure so as to be operative to retain the grinder or tool within the bore against dropping when the bore is finished and further adapted to impart a light outward pressure on the stones for finishing of the bore 30 with a light honing action so as to give a polished finished surface.

The foregoing and other features and advantages of the present invention will be understood by reference to the accompanying drawings, wherein like reference numerals 40 are applied to the corresponding parts in the several views.

In the drawings:

Fig. 1 is a view in side elevation of a honing tool embodying the features of the present invention;

Fig. 2 is a central vertical sectional view thereof;

Fig. 3 is a plan view thereof; and

Fig. 4 is a view in side elevation of a modified or elongated bearing sleeve element.

In the approved embodiment of the features of the invention as illustrated in the drawings, 1 indicates a vertically elongated cylindrical body or supporting member having a cylindrical bore or opening 2 extending therethrough of uniform diameter as shown. The body portion is provided with a series of radially extending upper and lower bearing apertures or openings 3 and 4 in vertical alignment and equi-distantly spaced about the circumference thereof. These radially disposed bearing apertures are outwardly elongated by the provision of 55 integral shoulders or bosses 5, arranged to give increased bearing area and to provide inner stops for the honing elements associated therewith.

The honing elements consist of the carborundum composition or like abrasive elements 6 fitted within metallic supporting trays 7 of channel form and within which the abrasive is secured by suitable cement. For the supporting of the abrasive elements or stones, bearing sleeves 8 are fitted within the respective bearing apertures 3 and 4, the sleeves 8 being provided with inwardly extending bores or openings 9, to receive pins or studs 10 rigidly secured by welding to the inner 60 sides of the channels 7. The pins 10, as indicated best in Fig. 2, are slotted inwardly from their free end portions to give an expansible gripping pressure for resiliently holding the stone elements in assembled position. The 65 sleeve members 8 at their inner end portions are formed with enlarged conical bearing surfaces 12, for engagement with complementary conical surfaces of an adjusting member now to be described.

For expanding or outwardly moving of the abrasive elements, there is provided a centrally positioned adjustor or actuator member 14 formed with upper and lower cylindrical portions 15 and 16 having a bearing fit within the bore 2 of the body member 1 and formed at 17 and 18 with downwardly and inwardly tapered or conical bearing portions positioned to engage the conical surfaces 12 of the stone bearing sleeves 8. The 70 75 80 85 90 95 100

adjuster member 14 is accordingly fitted to be 5
slidable vertical within the body member and
by reason of the engagement of the conical
surfaces, movement thereof will determine
the outward position of the abrasive elements
or stones and accordingly establish the ef- 10
fective operating diameter. To control the
adjusting movement of the adjustor member
14 and to accurately establish the operating
diameter of the stones, means are provided
15 for controlling the movement of the actuator
with a micrometer adjustment and indica-
tion. For this purpose the upper end portion
of the body member 1, is externally thread-
ed at 20 to receive thereon an adjusting sleeve
21 internally threaded and provided at its
upper portion with a knurled manipulating
portion 22. The adjusting sleeve 21 is
formed at its lower end portion with an ex- 20
ternal annular groove 23 to receive the in-
wardly projecting ends of screw studs 24 car-
ried by an annular collar 25 closely fitting
the sleeve 21 which is rotatable with relation
thereto. The collar member 25 is provided
25 with opposite radial bores 26—26 to receive
the extremities of a connecting or coupling
pin 27 passed centrally through apertures
28—28 formed in the upper portion of the
adjustor member 14. The construction ac- 30
cordingly provides, that upon rotation of the
adjusting collar 21 the resulting vertical
movement thereof will be imparted through
the pin 27 to the adjustor member 14 and
accordingly effect the adjustment or move- 35
ment of the abrasive elements through the
conical surface engagement hereinbefore re-
ferred to. For accurately determining the
movement of the stones in response thereto,
the adjusting collar 21 is provided with an 40
indicating mark or indentation upon the
outer surface of its side wall and the upper
surface of the collar member 25 is provided
with a series of graduation marks to coact
therewith for visibly determining the adjust- 45
ment of the collar and thereby facilitate the
adjustment of the stones to the effective op-
erating diameter desired.

As shown in Fig. 2 the upper end portion
50 of the adjustor member 14 is formed with a
centrally positioned recess or socket 30 within
which is positioned a coil spring 31 inter-
posed under compression between the coupler
pin 27 and the bottom wall of the recess 30.
Operatively related thereto and as shown, the
55 annular groove of the adjusting collar 21 and
the apertures 28 in the upper portion of the
adjustor member for the reception of the
coupling pin 27 are vertically elongated to
allow of a limited vertical movement or play
60 of the pin 27.

The body member 1 at its upper end por-
tion is suitably formed to have flexible cou-
pling connection with a driving spindle 35
adapted for connection with a portable driv-
ing motor. For this purpose the upper por- 65

tion of the body member is formed with a
bayonet slot 36 to be engaged by driving pin
37 carried by a spherical lower end portion
38 of the spindle 35. The driving connection
thus provided rotatably connects the body
portion 1 to the motor driving spindle with a
desired degree of play or flexibility allowing
the motor and grinding tool to be manually
supported and manipulated in the honing
operation. 75

In accordance with the present invention,
the strength of the coil spring 31 is propor-
tioned to impart a relatively light outward
pressure upon the stones which may be said
to be a supplemental and reduced pressure
and is to a degree particularly adapted as a
finishing and polishing operation. Accord-
ingly it will be understood that in the pri-
mary grinding or honing operation, after
inserting of the tool within the bore, the ad-
justing collar 21 will be screwed downwardly
to expand the stones into firm engagement
with the cylinder walls, in which operation
the spring 31 will be compressed to the limit
allowed by the vertical play of the pin 27,
the pin at this time having engagement with
the lower wall of the recess 28. The primary
grinding operation is then carried out by the
rotation of the tool and the progressive ad-
vancing of the adjusting collar to the degree
desired, under which conditions the primary
grinding operation is effected with a positive
advance of the adjustor member as distinct
from the resilient advance of said member
effected by the spring 31. Subsequently, with
the desired amount of metal having been
moved from the bore, a continued rotation
of the tool by reason of the supplemental
expansion of the stones under the influence
of the spring 31 will effect a desirable polish-
ing and finishing operation under a rela- 95
tively light pressure. 105

As will be further understood, the spring
31 further operates in a desirable manner to
retain the honing tool from falling within the
bore and further operates to take up the slack
of the parts. 110

The improved structure as described is
further desirable in that it provides a rela-
tively wide operating range considered with
115 relation to the varied sizes of cylinder bores
and further in the instance of bores of ex-
cessive diameter allows of conveniently ac-
commodating the tool thereto by substitut-
ing additional sleeve members 8 of increased
120 length, although utilizing the same trays and
stones, as illustrated in Figure 4.

While I have here shown and described an
improved embodiment of the features of the
present invention, it will be understood that
various modifications may be made therein
without departing from the scope of the ap-
pended claims. It is therefore intended that
such disclosure shall be interpreted as illus-
trative and not in a limiting sense. 125

Having described my invention, I claim:

1. A honing tool of the character described comprising a supporting member having a longitudinal bore and radially disposed bearings therein, bearing sleeves fitted to the bearings and having inner conical surfaces, said sleeves having bores opening outwardly, abrasive elements having inwardly extended pins fitted to the sleeve bores, an adjustor member slidably fitted within the bore of the supporting member and provided with similarly disposed conical or inclined portions positioned to engage the conical surfaces of the sleeves, means for adjustably moving the adjustor member to determine the position of the abrasive elements comprising an adjusting sleeve threaded externally upon the supporting member and formed with an annular slot, a collar fitted to the lower end 20 of the sleeve and having studs entering the groove, a coupling pin fitted to vertical slots in the supporting member and to openings in the adjustor member and with its extremities fitted to apertures in the collar, thereby to transmit axial movement of the adjusting sleeve to the adjustor member, the openings in the adjustor member for said pin being vertically elongated and said adjustor being formed with a socket positioned beneath the 25 pin and a compression spring fitted within the socket to engage the pin to be operative to exert an advancing pressure to the adjustor member substantially as described.

2. A honing tool of the character described comprising a supporting member having a longitudinal bore therethrough and radially disposed bearing apertures therein, bearing sleeve members slidably fitted to the apertures, said sleeve members having conical 30 inner end portions and bores inwardly extending from their outer end portions, trays provided with slotted pins fitted to the sleeve bores, abrasive elements carried by the trays and means for radially adjusting the abrasive elements consisting of an adjustor member axially movable within the supporting member and provided with conical portions positioned to engage the sleeve conical end portions and means for adjusting the position 35 of the adjustor member.

3. A honing tool of the character described comprising a supporting member having a longitudinal bore therethrough and radially disposed bearing apertures therein, bearing sleeve members slidably fitted to the apertures, said sleeve members having conical inner end portions and bores inwardly extending from their outer ends, trays provided with slotted pins fitted to the sleeve bores, abrasive elements carried by the trays and means for radially adjusting the abrasive elements comprising an adjustor member axially movable within the supporting member and provided with inclined portions 60 engaging the inner ends of the sleeves, posi-

tively acting means operative to move the adjustor for advancing the abrasive elements outwardly and supplemental resilient means associated with the positive adjusting means to be operative to impart advance movement to the abrasive elements with a relatively light pressure for a finishing and polishing operation.

Signed at Buffalo in the county of Erie and State of New York this 11th day of March, A. D. 1929.
